Patented Nov. 19, 1918.

UNITED STATES PATENT OFFICE.

JOHN KINTZ, OF SUBLIMITY, OREGON.

COMBINED GRADER AND DRAG.

1,285,228.

Specification of Letters Patent. Patented Nov. 19, 1918.

Application filed March 8, 1915. Serial No. 12,886.

To all whom it may concern:

Be it known that I, JOHN KINTZ, a citizen of the United States, residing at Sublimity, in the county of Marion and State 5 of Oregon, have invented a new and useful Improvement in Combined Graders and Drags, of which the following is a specification, reference being had to the accompanying drawings.

10 My invention relates to that class of devices ordinarily and chiefly used for graders and drags for the making of roads.

The object of my invention is to provide a device of this kind in which an adjustable part is arranged by means of which the soil can be shifted to a desired grade or be scraped or dragged to level a surface. I attain these objects, as well as other advantages, by the construction, combination 15 and arrangement of parts illustrated in the accompanying drawings which form a part hereof.

Figure 1 is a side elevation of the device.

Fig. 2 is a plan view of the same.

20 Fig. 3 is a sectional view of a part of the adjustable grader or scraper on the line 3—3 of Fig. 2.

Like letters and numerals refer to like parts throughout the figures.

25 A is a sled having parallel runners, namely, one runner B and a shorter runner B'. The runner B' is faced with a metal side 4' and both runners are beveled at their respective ends 5—5'. A transverse brace 6 connects the runners in a suitable position in the sled frame. A forward transverse brace 7 connects the runners at the end. Means 8 are provided to attach to some suitable motive power means. A plow bar extends from the beveled end 5 of the runner 30 B below the brace 6, its forward end being rigidly secured to the runner B. It is rigidly secured near its other end below and to the brace 6. It must extend diagonally from the runner B at an angle of 45 degrees thereto. The plow bar 9 is faced with metal 10.

35 A mold board 11 having a metal face 11' is secured to the rear end of the runner B by means of straps 12 having bolts 13—13'. The bolts 13' are nearest the free end of the board 11 which has within it vertical slots or spaces 14 which allow a play of the bolts therein when the board is moved upwardly or downwardly. A brace 15 has one end secured to the runner B near its end and the other end of the brace 15 is secured in a

suitable position on the mold board 11. The brace 15 is of some suitable material which will allow an upward movement of its end secured to the mold board. It extends at a right angle from the runner B. Upon the end of the brace 15, over the runner B, a rounded saddle 16 is rigidly secured. A stiff bar 17 has one end resting upon the seat of the saddle 16 and is retained there in adjusted position by means of the hand nuts 18. The other end of the bar 17 is rigidly secured upon the mold board 11 in a position which retains the bar at a right angle to the board. The mold board 11 is arranged at a suitable angle to the runner B' and must also be arranged positively at a suitable angle in relation to the direction of the plow bar 9.

40 It will now be seen that when it is desired to grade a road for example, or to shift the soil along longitudinal lines with the direction of movement of the machine, the bar 17 is adjusted so that the mold board has its lower edge practically on the same plane with the lower edges of the sled runners. Upon drawing the sled, the soil is shifted by the plow around its end in the direction of the arrows 19. It then passes against the mold board and is by it shifted outwardly between the free end of the board and the rear end of the runner B, where the soil is deposited in a course parallel to and outside of the runner B. I have found in practical use of my device that the best and really satisfactory 45 and complete results are obtained by having the plow bar 9 at an angle of 45 degrees to the runner B, and the diagonal position of the mold board 11 must be arranged entirely with relation to the aforesaid direction of the plow bar 9.

45 It will also be seen that the mold board may be raised a little distance by loosening the nuts 18 and by reason of the play given the bolts 13'. The board 11 is secured at a desired height by adjusting the nuts 18. This position is shown by dotted lines in Fig. 1. When the board 11 is thus raised the soil coming off the plow as before is allowed to pass below the mold board and the soil is scraped or dragged to an even surface longitudinally with the movement of the sled.

50 The simple construction of my device and the facility with which the mold board can be adjusted enables the operator successfully 55 and completely to grade or drag, as he may desire, with the least loss of time. This my

device accomplishes by reason of the arrangement and construction of the mold board and related parts which I contend are different from any other devices for similar objects.

Having fully described my device I claim:

A machine of the character described, comprising a sled frame having one runner B' suitably shorter than the other runner B, a vertical plow rigidly secured within the frame in a position extending inwardly from the forward end of the runner B at an angle of 45 degrees thereto and its opposite end terminating at a pre-determined distance from the runner B', a vertical mold

board having one end attached to the rear end of the runner B' and secured to the runner B by a brace so that the position of said mold board is at a suitable angle with relation to said plow bar, a saddle secured upon the runner B near its rear end, a bar 17 rigidly secured at one end to the mold board, its opposite end being securable in an adjusted position over said saddle, substantially as described.

JOHN KINTZ.
